21 Claims. (Cl. 179—18)

1

The invention relates to new and useful improvements in a telephone system or similar system for establishing connections.

In such systems a selected line or group of lines is reached via more than one selection stage and connecting lines between each of two consecutive stages of selectors, which may be either in the same or in different exchanges. More particularly, the invention relates to means for increasing the efficiency of the connecting lines and the selectors associated therewith.

It is known how one may obtain an increase of the efficiency of connecting lines and of selectors by the application of the so-called overflow principle. For instance, arrangements are known in which a selection takes place in such a manner that first a direct access is attempted to a pre-terminal group of selector switches. If these are not accessible along a direct route, then one out of another group of selector switches is seized and non-numerically operated in response to a discriminating signal from a preceding stage. Thus along an indirect route access may be had to another selector in the desired group. In this system the setting of the selector is so controlled that a free outlet of only one predetermined group can be seized at any one time, and a selector cannot hunt for a free outlet in two groups of outlets simultaneously. This is accomplished by the expedient that depending on the seizure of an outlet leading directly or indirectly to its destination, the operation of the seized selector, numerically or non-numerically, is determined in the first selector stage to which information must be conveyed whether a direct or an indirect outlet was found. According to said patent this is attained by permitting the first selector stage to hunt only in one group of outlets at a time and thus directly determine whether a direct or an indirect outlet is seized.

In my copending application No. 478,697, filed on March 10, 1943, an arrangement is disclosed for allowing a group selector switch, after it has hunted without result over a certain group of outlets, to hunt over another group of outlets leading to by-pass-selectors through which an outlet leading to the desired numerical group in another multiple split may be found. According to said patent application, special selector circuits are so arranged that a relay determines whether an outlet of the first or of the second kind is seized. If the relay is operated, then it causes the seized by-pass-selector to be set by means of a special train of impulses sent from

the first-mentioned selector or from an associated control circuit.

The system described in said patent application uses, therefore, selector switches with or without associated control circuits, and having a circuit arrangement which differs from the normal circuit. Furthermore, additional means must be provided in the selector switch or in one of the associated control circuits to make possible the setting of a seized by-pass-selector by means of these circuits. One of the resultant difficulties is that, if by-pass-selectors are not required from the beginning but only at a later stage, then either all the circuits must be equipped with unnecessary equipment, or part of the circuits must be radically modified.

These difficulties may be met by the use of a switching system, like the one disclosed in the application of S. Simon, J. Kruithof and M. den Hertog, Serial No. 472,623, filed January 16, 1943, and the applications of J. Kruithof, L. Kozma and M. den Hertog, Serial No. 473,278, filed January 22, 1943, and Serial No. 472,624, filed January 16, 1943.

By using the selector switches described in the last two patent applications, a register controller may be so arranged that a selecting and hunting selector switch will stop upon the receipt of two different kinds of signaling currents, i. e. of the signaling current which is received from the desired group of outlets, and of another signaling current which is received from a group of outlets to which by-pass-selectors are connected. The register is then in a position to continue with the next selection, depending on the signal received (i. e. if an outlet in the desired group was seized), or to insert an additional selection, which sets the seized by-pass-selector onto the group of desired outlets associated therewith. This eliminates special provisions in the selector switches or associated control circuits, and the normal group selector circuits may be used. All functions required for the seizure and setting of a by-pass-selector are controlled from the register controller.

One of the characteristic features of the invention consists in providing for the possibility of permitting a selector to hunt for a free outlet in more than one group during the same selecting operation. The outlets of each group send characteristic signals to a preceding switching stage to indicate to which group the seized outlet belongs. This preceding switching stage may accordingly determine the way in which the seized selector has to be set. The arrangement may be

such that at the beginning of the hunting movement, the first-named selector tries to find a free outlet in a desired group and also in an alternative group. The desired group is given preference because the selector will, during the hunting movement, move first over all the outlets of the desired group, and only then over the outlets of the alternative group. The selector may first try to find only a free outlet of a desired group, and if such a free outlet is not available, then the functioning of the selector is modified to hunt for a free outlet in the desired group and in an alternative group during the same selecting operation.

According to another feature of the invention the selector, which was in a position to seize outlets of two different groups, sends a signal from the seized outlet to a preceding stage in order to indicate whether the seized outlet is of the desired or of the alternative route. In the preceding stage the signal will cause the performance of an additional selection to reach a selector of the desired direction by an indirect route, if an outlet of the alternative route was seized. No additional operation takes place if an outlet of the desired route was seized.

A further characteristic feature of the invention is that, depending upon the switching system chosen, the setting of the selector seized by the alternative way takes place in a non-numerical way, or this selector may be set by a repetition of the selector setting in the preceding selector stage.

According to still another characteristic feature of the invention, means may be provided to release a selector if it selects an alternative outlet which will not give access to the desired line, and to operate it to seize another alternative outlet, the associated selector of which will hunt for an outlet in the desired direction.

According to a further feature of the invention, when a selector has tried all the available alternative outlets and none of these gives access to an outlet in the desired direction, then it starts its function anew, and will first try to find an outlet in the desired direction along the direct route.

Six embodiments of the invention will be described in connection with the drawings in which Figs. 1-5 schematically represent different ways in which consecutive selector stages may be connected by junctions; Figs. 6-10 and 14 diagrammatically show details of a connecting circuit with an associated register; Figs. 11, 12 and 12(a) show different ways of cross-connecting in the register, to be used as indicated in Fig. 18, 19 or 20; Fig. 13 shows a group selector of the type described in the application Ser. No. 473,278; Figs. 6-14 must be put together for the six different embodiments in the way indicated in Figs. 15-20.

All six embodiments are variations of the method of group selector setting described in application Ser. No. 473,278. The main feature of the invention will be described with reference to Figs. 1-5, and the operation of the different embodiments will be explained with reference to Figs. 6-14.

The group selectors shown in Figs. 1-5 are all of the type in which in one single cyclic movement of the selector all the outlets are wiped over by one or more sets of brushes. The contacts are divided in ten or more groups or "levels" corresponding to just as many different numerical groups of second group selectors, each of which is assumed to have access to a certain thousands group.

In Fig. 1 four of these groups are shown. If a connection is desired to the second thousands group of lines, then the first group selector will hunt under the control of the register, with the purpose of finding a free outlet in the second level.

Let us first assume that at the commencement of the hunting the selector, under the control of the register, can seize a free outlet in the second as well as in the third level. The terminal banks of the selector are, however, so divided that the terminals belonging to the same level are all located one next to the other, and the terminals belonging to different levels follow one another in the normal order. Thus, first all the terminals of level 2 will be tested before the first terminals of level 3 are reached. In the same way, all terminals of level 3 must be tested before a terminal of level 4 is reached, etc. When the first group selector finds an outlet in the desired group, in this case in the second level, the register responds in the normal way, i. e. it will numerically set the second group selector in accordance with the received hundreds digit.

If, however, the first group selector does not find an outlet in level 2 but only in level 3, then the register will cause the performing of an additional selection and the seized second group selector of the third level will be non-numerically caused to select an outlet in its 11th level. This 11th level has outlets connected to the second group selectors which have access to the second thousands group. When one of these second group selectors is seized, the register responds and sets this group selector according to the hundreds digit received from the calling party.

In a similar manner, calls to any other level of the first group selector may overflow to the next level, if no free outlet is found in the desired level. When, e. g. level 3 is desired, an alternative route may be found via level 4, and when the last level is desired, an alternative route may be found via the first level.

The advantage of this arrangement is that, for each call, the number of available outlets in the first group selector is twice as large as when selection is made only via a single level, and thus the efficiency of the outlets is increased. Since during the same operation the selector may hunt in two levels, if no free outlet is formed in the second level then the hunting may be continued until an outlet becomes free in one of the two available levels. During each new cyclic movement of the selector, preference is given to the outlets of the desired level. When the register receives a signal from the selected outlet, or when the group selector selects an outlet in the desired or the alternative level, the register will control the performance of the next selection, or it may control the setting of the so-called overflow selector in the 11th level. In previous arrangements the selector could test only one level on one operation and if it found no free outlet then the connection could be built up only via the alternative level, even if an outlet in the desired level became free before an outlet in the alternative level had been found.

The circuit diagrams for this system are the ones indicated in Fig. 15.

A second embodiment will now be described with the aid of Fig. 1.

The first group selector is only initially operated to seize an outlet in the desired level. The 75 outlets of all levels may now be distributed in any

arbitrary way throughout the bank of the selector, as is customary in selectors of this type.

By distributing the outlets so that a few but not all the terminals of all levels will be consecutively reached when the first part of the bank is tested, then in most cases the short hunt over a small part of the arc will be sufficient.

If the wipers of the selectors move over all the contacts of the bank arc, a signal is sent to the register to perform a change-over to operate the selector to hunt for outlets in two different levels.

During the second and possibly further rotations of the selector brushes, the outlets of the desired level, and also the outlets of the next level are tested until a free outlet is found in one of the two levels. The register circuit receives a signal, just as in the case described above, to indicate whether the selected outlet belongs to the one level or to the other.

The circuits should be put together as shown in Fig. 16.

In Fig. 2 an embodiment is shown, whereby two consecutive levels are paired and calls directed to an odd numbered level may overflow to the following even numbered level, while calls directed to an even numbered level, may overflow to the preceding odd numbered level, provided, of course, that no free outlet is found in the desired level.

This system operates according to the same principle as described for the second embodiment of Fig. 1, and the circuits are used as shown in Fig. 17. Both embodiments offer the same advantages as described above for the first embodiment according to Fig. 1.

Fig. 3 illustrates a single group selector stage, e. g., a first group selector, of which certain levels serve for the connection of local group selectors via local junction lines, whereas other levels are used for reaching distant group selectors via outgoing trunks or junction lines.

In order to increase the efficiency of the outgoing junctions, calls directed to each of the levels, may be rerouted via a number of overflow terminals common to these levels, special overflow selectors OS are provided, which give access to other trunks in the same outgoing direction. As indicated in the drawing, the one hundred available contacts or terminals of the group selector arc are divided into 5×14 sets of contacts for local outlets, 5×5 sets of contacts for outgoing outlets, and the remaining five sets of contacts serve for reaching a group of overflow selectors OS. The efficiency of the local outlets will be relatively high, because a group of fourteen instead of the customary group of ten outlets is used. At the same time, the efficiency of the outgoing outlets is also increased, because the total number of available outlets for each of the five groups is twenty-five, i. e. five connected directly to the first group selectors and twenty accessible via the overflow selectors. This is so because the arc of one hundred contacts in the overflow selector is divided into five groups, each having twenty sets of contacts, corresponding to the five levels over which the traffic may be diverted via these selectors.

The selectors operate as follows:

The first group selector is controlled from the start by the register circuit so that it can test either the outlets of the desired level or it can seize one of the outlets leading to the overflow selectors OS. Since these outlets are connected to the last sets of contacts of the arc, the first

group selector can reach these only if none of the outlets in the desired direction is free.

When a free outlet in the desired direction is found, the register circuit responds by controlling the next numerical selection. When one of the outlets to the overflow selectors OS is seized, the register circuit repeats the first group selector setting. The overflow selector will, therefore, be moved to a level corresponding to the desired first group selector level and will select the outlet in the desired direction connected thereto. The levels of the overflow selectors, although their number is smaller than that of the first group selectors, are selected in the same manner as the first group selector level. When an outgoing trunk is seized over one of the levels of the overflow selectors, the register will control the next numerical selection.

The circuits in this system are used as shown in Fig. 18.

Fig. 4 illustrates an arrangement like in Fig. 3, but in which the first group selector has two overflow levels, each serving for a part of the other levels. Thus, a call to one of the levels 1-5, which may be used for local calls, will, if no free outlet is found, overflow to the overflow level 6, giving access to a group of overflow selectors OS₁ to which other local outlets are connected leading in the same direction as those connected to levels 1-5 of the first group selector. Calls to levels 7-11, which may be used for outgoing junctions to other exchanges will, when no free outlet is found, overflow to level 12, which gives access to a second group of overflow selectors OS₂ to which other outlets to the same distant exchanges are connected. The operation is as follows:

When a selector is set to one of the levels 1-5 under the control of the register, it may seize an outlet either in the desired level or in level 6. The outlets of level 6 are connected in the arc in such a way that they can only be reached after all the outlets of the levels 1-5 have been tested. If one of the levels 7-11 is desired, then the register will operate the selector to seize an outlet either in the desired level or in level 12, the latter being accessible only after the first five have been tested.

When an outlet in the desired level is found, the register is notified thereof and responds by performing the regular numerical setting in the next selector. If, however, an outlet in an overflow level is seized, then the register repeats the first group selection to control the overflow selector. The different levels of the overflow selectors are reached by the same numerical operations as the corresponding levels of the first group selectors.

A total of twenty-nine outlets for each of the ten levels of the first group selectors may be reached. Nine outlets are connected directly to the first group selectors themselves, and twenty outlets are accessible through the overflow selectors. Although the number of outlets per level is considerably higher than by the normal use of a one hundred point selector, and the efficiency of all the outlets is considerably increased, this is attained by adding only the overflow selectors which are used only for traffic peaks.

The circuits for this arrangement are the ones indicated in Fig. 19.

Obviously, the wiring of the terminal banks of the different selectors, illustrated in Figs. 3 and 4, can be arranged in different ways. The numbers for the different groups of outlets shown in

these figures are mentioned only by way of example.

Fig. 5 represents a modification of Fig. 3. It shows a number of primary first group selectors PGS, each having ten groups of outlets, to which second group selectors are connected. The number of second group selectors required for each level is so large that the multiple of the primary first group selectors must be split into a number of parts. By way of example, it is assumed that the multiple for each of the levels is divided into four parts. The symbol for a single first group selector PGS in the figure represents all primary first group selectors which have a common multiple. By way of example, a number of second group selectors are shown as accessible over the first level.

The first group selectors have an eleventh level, the contacts of which are connected to secondary first group selectors SGS. These have access to other multiple splits than are accessible to the corresponding primary first group selectors. For instance, the contacts of level eleven of the primary first group selectors, which have the first multiple split in common, give access to secondary first group selectors, which are connected in multiple to the second, third or fourth multiple splits. With this arrangement any arbitrary part of the outlets for each level may be reached. The operation is as follows:

When a primary group selector, giving access to the first multiple split, is set on the first level, then the setting takes place under the control of the register in such a way that the selector may during that operation hunt for a free outlet of the first level, or for a free outlet of the eleventh level. In case a free outlet in the first level is found, this is communicated to the register, which responds by performing the normal second group selector setting.

When a free outlet is found in level eleven, this is also communicated to the register, which responds by repeating the first group selector setting to the seized secondary first group selector through which another multiple split and, therefore, another group of second group selectors for the same direction, is reached. The contacts of level eleven are distributed over different secondary first group selectors, which are connected to different multiple splits.

When a secondary first group selector, belonging to the second multiple split, has been seized, it is set to the first level. The arrangement is such, that this selector can test this level and also level eleven during the same operation. If the selector does not find a free outlet in the first level, it will hunt until it finds a free outlet in level eleven. If the selector arrives on the last contact of the eleventh level, to which no secondary selector is connected, then the same operations will be performed as upon seizure of any contact set belonging to level eleven, that is to say, the selector will stop and a signal will be sent to the register to indicate that the brushes stopped on a contact of level eleven. The register will then signal the primary first group selector, in the present case, the selector in the first multiple split, and cause the release of the group selector in the second multiple split. Then the register starts to set once more the first-mentioned primary first group selector. This group selector will leave the contact on which it was first set (the secondary first group selector in the second multiple split has not yet returned to the home position and is, therefore, inaccessible),

and will again start to hunt for a free outlet. Preferably a secondary first group selector will now be seized in the next multiple split, whereby the next group of outlets leading to the desired second group selectors will be tested. If all these outlets are busy then the above-described operation may be repeated, so that the primary first group selector in the first multiple split may consecutively be connected to a secondary first group selector in all other multiple splits, until a free outlet is found. When finally all multiple splits have been unsuccessfully tested, the first group selector returns to the beginning of the arc on level one and starts testing again the outlets in the first level.

The circuits for the arrangement just described are the ones indicated in Fig. 20.

The different embodiments of the invention according to Figs. 1-5 will now be described by reference to Figs. 6-14. The circuit diagrams should be combined for the six modifications as indicated in Figs. 15-20.

SYSTEM OF FIG. 1 (KEY SHEET FIG. 15)

25 The upper part of Fig. 6 shows a connecting circuit, one end of which is connected via one or more line finders and register link finders or the like, to the line of a calling subscriber and the other end to a first group selector shown in Fig. 13 via register link finders and connecting links. The connections are shown through which during the establishing of a connection, the connecting circuit is connected through register finders to a register circuit, some of the details of which are shown in the lower part of Fig. 6 and in Figs. 7 and 8.

(a) Receipt of the digits

40 The digits of the desired subscriber's number are dialed by the calling subscriber in the known way by means of his calling dial, which will cause relay *Isr* to release a number of times corresponding to the digit dialed. When relay *Isr* first operates, i. e. when the register is seized, the relays *Lbr* and *Lhr* are energized. Relay *Lbr* is a slow releasing relay and remains operated during the sending of the impulses.

45 The first digit is recorded by a step-by-step switch *SM₁*. At the first interruption by the dial, *SM₁* is operated in the circuit: ground, back contact of *Isr*, front contact of *Lbr*, winding of *Lmr*, back contact of *Dir₁*, winding of *SM₁*, battery. Relay *Lmr* operates at the first pulse and remains operated during the dialing of each digit. *SM₁* takes a step for each de-energization of relay *Isr* and finally stops in a position corresponding to the first digit sent.

50 During the dial interval between the first and second digits, relay *Isr* remains operated long enough to release relay *Lmr*, so that the brushes of step-by-step switch *IM*, which was energized over a front contact of relay *Lmr*, move one step during the dial interval. *IM* moves its brush *a* to position 1 and relay *Dir₁* operates. This relay switches the in-stepping circuit from *SM₁* to *SM₂*, so that the second digit will be received by *SM₂* in the same manner as the first digit by *SM₁*. At the end of the second digit *IM* again takes a step, thereby energizing relay *Dir₂*. All the following digits are recorded consecutively in the same manner by different step-by-step switches. As this is no essential part of the invention, only three of these step-by-step switches are shown.

(b) *Alternating current test*

It will now be assumed that the first digit was 2, so that the second level of the first group selector must be selected. It will be clear from the description of Fig. 1, that in this case means must be provided to hunt for an outlet in the third level if all the outlets of the second level are busy.

As soon as the first pulse of the first digit is recorded by SM₁, the first group selector leaves its home position and starts the selection of a free second group selector in the group determined by the position of SM₁. As is usual for this type of group selectors, the outlets of level one are connected to terminal or contact sets so spaced from the home position that, if the first digit is not 1, then a second pulse may be received by the register and SM₁ take a second step, before the group selector can reach the first contact set of level one. Similarly, the group selector can reach the first contact set of level two only after more than two pulses have been received, in case the first digit is not 2, etc. In the case under consideration, SM₁ stops in position 2 and only after that will the group selector arrive at the first set of contacts belonging to level two.

Relay Ar in the first group selector is operated in the following circuit, as soon as the register is seized: ground, brush and home contact *a* of SM₁, front contact of Lhr, *b* wire, back contact of Br, back contact of Ar, winding of Ar, battery.

Relay Ar remains operated over the *d* wire to ground via a front contact of relay Lhr.

The power magnet of the selector is energized when the register takes one step and the brush carriage starts to rotate, the circuit being: ground, brush and contact *l* in arc *a* of SM₁, contact N and brush *c* of OM, back contacts of Vtr, Vtr, Ftr and Vrr, *a* wire, back contact of Br, front contact of Ar, power magnet P, battery.

The selector setting takes place in the manner described in the application Ser. No. 473,278, by comparing the phase angle of an alternating current of a free outlet over which the group selector wipes with the phase angle of a reference current in the register. The phase angle of the reference current is dependent on the number dialed and only when a selector brush wipes over an outlet to which an alternating current of the same phase angle is connected will a signal receiver in the register operate and stop the selector.

In the present case the group selector must be able to stop on outlets of two different levels to which, therefore, alternating currents having two different phase angles are connected. Means are provided in the register to compare these two phase angles with those of two different reference currents. These means are the two signal receivers I and II in Fig. 8. The reference currents for these two signal receivers are determined by the dialed number.

The reference current for signal receiver I is supplied through the following circuit: from an alternating current source having the required phase angle to contact 2 in arc *b* of SM₁, contact N in arc *d* of OM, back contact of Or, primary winding of the transformer T₁ in signal receiver I to ground.

The circuit for the second reference current is: from alternating current source with required phase angle to contact 2 in arc *c* of SM₁, contact N in arc *e* of OM, primary winding of transformer T₂ in signal receiver II to ground.

The connections to the arcs *b* and *c* of the

different step-by-step switches SM₁, SM₂, etc., are so arranged that the current sources to the contacts of arc *b* are shifted one step with respect to arc *c*. In this way reference currents with phase angles of two consecutive values are connected to the two signal receivers enabling them to control selection in two consecutive levels of the group selector.

The circuit for the signaling currents received from the tested outlets of the first group selector is as follows: alternating current source, resistance of 100 ohms in the tested second group selector (same as first group selector), home contact of group selector, busy jack BJ, back contact of Ar, *d* wire, *d* brush of the first group selector (Fig. 13), back contact of Br, front contact Ar, *c* wire, back contact of Str, and then in parallel the primary windings of the transformers HC₁ and HC₂ in the two signal receivers to ground.

The reference currents are so selected that the signal receiver I will respond when the desired level is hunted over by the selector, in the present case level two, and signal receiver II when the next level is tested by the selector.

If a free outlet is found in level two, signal receiver I will respond in the known manner by the ionization of tube B₁, whereupon relay Vtr operates and the selector stops.

Relay Vtr energizes relay Ftr in the circuit: ground, brush and contacts 1 and 2 in arc *a* of SM₁, home contact N and brush *c* of OM, front contact of Vtr, back contact of Vtr and Fhr, winding of Ftr, battery.

Relay Ftr prepares a locking circuit for itself through the winding of relay Fhr and opens the circuit in which relay Chr was energized upon the energization of Dtr. Chr disconnects the potential that was applied to the tube B₁, this tube becomes extinguished and relay Vtr releases.

The circuit for the power magnet of the group selector was opened at the back contact of relay Ftr. The release of relay Vtr does not, therefore, cause the group selector brushes to move again, but relay Fhr operates in series with relay Ftr via a front contact of relay Ftr and a back contact of relay Vrr to ground on a front contact of relay Lhr. Relay Fhr again closes the circuit for relay Chr, so that the signal receiver can again respond when comparing the signaling current received with the selected reference current. The tube B₁ is now ionized for the second time and relay Vtr is operated for the second time. This takes place before the slow operating relay Kir could be energized via the back contact of relay Vtr and front contacts of the relays Ftr and Fhr. The operation of relay Vtr results in the closing of a circuit for relay Str via a front contact of relay Fhr.

(c) *Direct current test and switching through of register to following selecting position*

The operating of relay Str indicates that the alternating current test is completed and that the register circuit will now apply the direct current test to the found outlet. Reference is made to the description in the above-mentioned application Ser. No. 473,278, in which a similar circuit is described. When the direct current test passes successfully, the relays Tr and Dtr operate and connect ground to relay Sar over the following circuit: ground, front contact of Dtr, back contacts of Vtr and Vtr, winding of Sar, battery. Relay Sar remains operated via the interrupter of OM and closes a circuit through the winding of this switch. Relay Sar cannot release until it

is made certain that OM is fully energized and its brushes move by one step, whereupon relay Sar releases. As soon as relay Dtr releases as a result of the removal of the test potential from the selected outlet, relay Sar releases and OM moves one step into position 1, in which it can control the next selecting operation according to the second digit that was dialed. Relay Sar operates also relay Vrr, whereby the locking circuit for relays Fhr and Ftr is opened. These two relays are released. The relays Str and Vrr release after relay Sar is de-energized.

The release of relay Vrr closes again the circuit for relay Chr, so that the register is now ready to control the next selector setting.

(d) *No free outlet available in the desired level*

If no free outlet is available in the desired level, then the selector continues its hunting operation and its brushes will wipe over the outlets of the next level. If one of these outlets is free, the signal receiver II in the register responds, because the alternating current at this outlet has the same phase angle as the reference current which is connected to the signal receiver II.

The tube B₂ is therefore ionized and the relay Vtr operates. This stops the selector on the selected outlet. Relay Vt_{2r} is now operated in the circuit: ground, brush *a* of SM₁, contacts 1 and 2 in *a* arc, contact N and brush *c* of OM, back contact of Vtr, front contact of Vtr, back contact of Vt_{2r}, winding of this relay, battery. Relay Vt_{2r} remains operated, under the control of a back contact of relay Vrr, to ground on a front contact of relay Lhr and switches the ground on the front contact of relay Vtr through to the winding of relay Ftr.

Relay Ftr has the same functions as mentioned in chapter *b*, so that a second test of the received alternating current takes place, upon the successful termination of which relay Str operates.

(e) *Direct current test*

The direct current test now takes place in the known manner and the relays Tr and Dtr operate. The ground on the front contact of relay Dtr is now switched over a front contact of relay Vt_{2r} to operate relay Vt_{3r}, which locks up independent of relay Vt_{2r} direct to the front contact of relay Dtr.

(f) *Register controls the adjustment of the bypass-selector on the eleventh level*

The energization of relay Vt_{3r} results in the energization of relay Vrr, whereupon relays Ftr, Fhr, Vt_{2r} and Chr release. Also, the tube B₂ of the signal receiver is extinguished. A second result of the operation of relay Vt_{3r} is, that relay Or is operated and locks up over the interrupter contact of OM.

When the first group selector is connected through and the direct current test potential of the seized second group selector is removed, the relays Tr and Dtr release, whereupon the relays Vt_{3r}, Vrr and Str also release.

The register is now in a position to control the next selection, although the brushes of switch OM have not taken an additional step. The reference current for signal receiver I is now no more obtained via arc *b* of step-by-step switch SM₁, but via the right hand outer front contact of relay Or which connects the primary winding of Tr direct to an alternating current source having a phase angle corresponding to that existing on the outlets of the eleventh level. Signal receiver II is rendered inoperative because

75 65 70

the battery for the control electrode of tube B₂ is disconnected and replaced by ground. This tube can, therefore, not respond, not even if signal receiver II receives signaling and reference currents having the same phase angle.

The seized second group selector can now select only an outlet in the eleventh level, to which the desired thousand's outlets are connected. When a free one of these outlets is found, signal receiver I responds, and the register operates in the way described in chapter *b*. Upon the termination of the direct current test, relay Sar operates since relay Vt_{2r} is not now operated. The brushes of OM move one step and relay Or releases upon the opening of the interrupter contact of OM.

15 The register is now in condition to control selection in accordance with the second digit which the subscriber dials.

(g) *Further operations*

20 For further operations of the register circuit in cases where the selected outlet has no free direct current potential, or where hunting is performed by the selector during the receipt of the dialed number, reference is made to the description of said application Ser. No. 478,278.

SYSTEM OF FIG. 1 (KEY SHEET FIG. 16)

The circuits used are the same as in the first 30 case, with the exception that Fig. 10, as compared to Fig. 8, has three relays Epr, Ehr and Tlr added, which alter the operation of the register circuit, in case no free outlet is available in the desired level, as follows:

35 (a) *Seizure of outlet in eleventh level of first group selector*

The primary winding of transformer T₂ of signal receiver II is connected via a back contact 40 of Tlr to an alternating current source, which has the same phase angle as the alternating current connected to level eleven. Therefore, if no free outlet is found in the desired level, the first GS will test an outlet of level eleven. This level eleven consists in this case of a single contact set, the last contact in the arc, to which alternating current of the above-mentioned phase angle is connected, but to which no second group selector is connected. Alternatively, instead of using a contact set in the arc, this eleventh phase 45 may be connected by closing a contact by means of the brush carriage, just before it returns to its home position. This alternating current will actuate signal receiver II and thus cause the energizing of relay Vt_{2r}, which in turn energizes relay Epr. Relay Epr prepares a locking circuit for itself to ground on the interrupter contact of OM, and opens the circuit for relay Chr, via a back contact for relay Chr, whereupon tube B₂ extinguishes and relay Vtr is released. Relay Ehr is operated in series with the locking circuit of relay Epr, and relay Tlr is energized via a front contact of relay Ehr.

(b) *Second hunting operation*

The circuit for the power magnet of the selector, which was first opened by relay Vt_{2r} and then by a back contact of relay Epr, is now again closed by a front contact of relay Tlr. Moreover, relay Tlr has changed the manner in which the register 55 controls the hunting.

The signal receiver I remains in the original condition and will respond to alternating current characteristic for the dialed first digit under the control of switch SM₁. Signal receiver II is dis-

connected from the alternating current source having phase displacement II, and instead of this reference current, a reference current determined by the dialed number is now connected to signal receiver II via arc *c* of SM₁ and a front contact of Tlr. This alternating current source corresponds to the level next to the desired level.

The brushes of the selector perform a second rotation in the same way as described for the arrangement of Fig. 15 for the first rotation.

(c) *No free outlet is found in the desired level during the second rotation*

When, during the second rotation of the brushes, a free outlet is found in the level next to the desired level, signal receiver II will respond and relay Vtr will be operated. The following circuit is closed for relay Vtr; ground, brush *a* and contacts in *a* arc of SM₁, contact N and *c* brush of OM, back contact of Vtr, front contact of Vtr, front contact of Ehr, back contact of Vtr, winding of Vtr, battery.

The operation of relay Vtr is the same as described for the case of Fig. 15 and, therefore, a second alternating current test will take place, as well as a direct current test of the selected outlet. The operation of the direct current test relays Tr and Dtr results in the next selector setting without the necessity of moving the switch OM an additional step.

(d) *Register controls the adjustment of by-pass-selector on the eleventh level*

By the operation of relay Or the condition of the two signal receivers is changed in the same way as described in connection with Fig. 15, so that the by-pass-selector will hunt for an outlet in the eleventh level. This outlet leads to a second group selector in the desired thousands group. After that the brushes of switch OM advance one step and the register is ready for the control of the second group selector according to the dialed second digit.

THE SYSTEM OF FIG. 2 (KEY SHEET FIG. 17)

This is a modification of Fig. 16, in that the connections of the arcs *c* of the different step-by-step switches SM₁, SM₂, etc., are wired different.

As explained in the general description of Fig. 2, if the desired level number is odd, then during the second rotation of the switch brushes, the next even numbered level may be seized, whereas, if the desired level is even numbered, then during the second rotation of the switch brushes the preceding odd numbered level may be selected. The circuits are the same as those of Fig. 16, with exception that in Fig. 9 the connections of the arcs *c* of the step-by-step switches SM₁, etc., are adapted to the new requirements.

If the first digit is odd, then the reference current for signal receiver I, which is supplied via arc *b* of SM₁ during the second rotation of the selector brushes, will have a phase angle corresponding to the phase angle of the alternating current connected to the outlet of the desired level. Signal receiver II operates in this case on a reference current supplied over arc *c* of SM₁, which has a phase angle corresponding to that of the next level.

In the case of an even digit, the phase angle supplied over arc *b* again corresponds to that of the desired level, but that supplied over arc *c* corresponds to the phase angle of the current supplied over the preceding level.

SYSTEM OF FIG. 3 (KEY SHEET FIG. 18)—REGISTER CONNECTIONS ACCORDING TO FIG. 12(a)

The circuits are the same as those for Fig. 15, except that the reference currents are controlled in a somewhat different manner by the arcs *c* of the different step-by-step switches, on which the successive digits are registered.

(a) *Hunting condition of first group selector*

The first group selector is so controlled by the register that an outlet in the desired level may be selected by signal receiver I, the reference current to transformer T₁ being supplied over arc *b* of the step-by-step switch or, if no free outlet is found in this level, the selector may hunt for an outlet in level eleven. To this end, the signal receiver II is connected over arc *c* of the step-by-step switch to the alternating current source with the corresponding phase angle. In accordance with Fig. 3 the connections in Fig. 14 are so modified (Fig. 11) that the alternative seizure of an outlet in level eleven takes place only in case the selected level is one of the levels 6—10. This is accomplished by the connection of the reference current for signal receiver II only in the above-indicated positions of SM₁. The other terminals of SM₁ are connected to an alternating current source having characteristics which do not represent any level in the group selector arc. The purpose of this is to keep the signal receiver by means of this reference current continuously in the inoperative position, because in the absence of reference current, response would take place immediately.

For the digits, for which the selector setting takes place without alternative selection of the eleventh level, the signal receiver II remains inoperative because the ground supplied over the corresponding contacts in the *f* arc of OM, will keep the potential on the controlling electrode of tube B₂ so low that it will not respond.

Other modifications are possible by suitably wiring the register. Thus, one may vary the number of levels, for which level eleven must serve as alternative, and the successive digits, for which this alternative operation must be performed.

(b) *Operation of the register, if outlet in level eleven has been seized*

As a result of the operation of relay Vtr upon the functioning of signal receiver II, the relay Or is operated at the moment the selected outlet is definitely seized and the register will then control the subsequent selector setting, without moving the brushes of step-by-step switch OM. This takes place in the same way as was described in connection with Fig. 15. This second selector setting is so controlled by Or that the signal receiver II is rendered inoperative because direct ground is supplied to the controlling electrode of the tube B₂. The overflow selector OS will, therefore, be sent in accordance with the first digit, i. e. in accordance with the position of SM₁, without any alternative operation.

After the overflow selector has found a free outlet, OM will take a step and the register will be ready to perform the setting of the second group selector in accordance with the second digit.

SYSTEM OF FIG. 4 (CIRCUITS ACCORDING TO FIG. 19)

This case differs from the foregoing only in that for part of the levels one alternative level is

present, and for another part of the levels a second alternative level. The first alternative level is characterized by the presence of alternating current with a determined phase angle, e. g. $\varphi 11$, and the second alternative level by another alternating current with a phase angle of e. g. $\varphi 12$. The desired result is attained by connecting signal receiver I via the *b* brush of step-by-step switch SM_1 with the reference current corresponding to the signaling currents in the desired level. Signal receiver II is connected to a reference current $\varphi 11$ or $\varphi 12$, under the control of arc *c* of the same step-by-step switch, depending on the selection of the first or the second level as the alternative to the desired level. The circuits are, therefore, like the one described in connection with Fig 18, with exception of the jumpring and the provision in the group selector arc a second alternative level characterized by alternating current $\varphi 12$.

SYSTEM ACCORDING TO FIG. 5 (KEY FIG. 20)

When a group selector tests in an alternative level, the last selector setting will be repeated in the seized by-pass-selector. If this by-pass-selector hunts also in an alternative level, then the register circuit takes care of it, that the by-pass-selector be released, and that the first group selector start hunting again under the same conditions as the first time. The result may be that either another by-pass-selector will be seized, in which case the preceding operation is repeated, or that the first group selector will find a free outlet in the desired level. This will be signaled to the register as soon as it can respond by the setting of the next digit.

All these operations are already known from the foregoing description, with exception of the way in which a group selector releases a by-pass-selector and starts hunting again. In order to make this clear, the preceding operations will also be briefly described.

(a) First selector setting

During the first selector setting signal receiver I is connected to the reference current corresponding to the desired level, i. e. via arc *b* of the step-by-step switch on which the digit is registered. Signal receiver II receives a reference current corresponding to the signaling current which is present in the alternative level eleven. When an outlet in level eleven is seized, signal receiver II responds and relay Vtr_1 is operated, as are also the relays Vtr_2 and Ftr . Tube B_2 is extinguished, relay Vtr_1 releases and relay Ftr is operated in series with relay Ftr . The second alternating current test is then made and relay Vtr_1 operates once more, relay Str is energized, and the direct current test starts. Relays Tr and Dtr operate and the latter energizes relay Vtr_3 via the change over contact of relay Vtr_2 . Relay Vtr_3 applies ground for operating of relay Or_1 and this relay prepares a holding circuit for itself via the interrupter contact of OM .

As soon as the by-pass-selector is definitely seized, the circuit to the direct current potential is opened and the relays Tr and Dtr release, followed by relay Vtr_3 . Relay Vtr_3 had also operated relay Vrr , which interrupted the energizing circuits of the relays Ftr , Fhr , Vtr_2 and Chr . After Vtr_3 relay Vrr also releases, while relay Chr operates. Moreover, the ground for relay Or_1 is opened, so that relay Or_2 is now operated in series with relay Or_1 . The register circuit is now ready

for the setting of the by-pass-selector without OM being moved, so that the by-pass-selector is set according to the first digit, since the connections to the reference currents of the two signal receivers are not changed.

(b) By-pass-selector tests in the alternative level eleven

10 The signal receivers are now connected in the same way as for the setting of the first group selector. The only difference is, that the relays Or_1 and Or_2 are operated. If the by-pass-selector will now also hunt for an outlet in level eleven, then a circuit will be closed for operating relay Bdr when the alternating current test takes place for the second time and relay Vtr_1 operates for the second time; this circuit is as follows: ground, brush and *a* arc contacts of SM_1 , contact *N* and brush *c* of OM , back contact of Vtr , front contacts of Vtr_1 , Vtr_2 and Fhr , back contact of Bdr , front contact of Or_2 , winding of Bdr , to battery.

Relay Bdr operates and remains energized over make-before-break contact combinations, independent of relay Or_2 to ground via the front contact of relay Vtr_1 . It opens also the temporary operating circuit for the relays Or_1 and Or_2 so that these relays release, and closes a ground to wire *c* of the first group selector, which wire leads to the point where the locking winding of relay Br is connected in the first group selector to the series resistance of 600 ohms. The relay Br is, therefore, short-circuited and opens the circuit through which signaling current is supplied to the signal receivers. The release of relay Br causes the first group selector to return to the condition in which the hunting for a free outlet may take place (only relay Ar operated).

When relay Or_1 is released, it closes a ground via a back contact and a front contact of relay Bdr for the operating of relay Vrr . This relay opens the circuit for relay Chr (which extinguishes the tube B_2 and releases relay Vtr_1) and the circuit for the power magnet of the first group selector over two back contacts. It opens the locking circuit for the relays Vtr_2 , Ftr and Fhr via a third back contact, whereby relay Bdr also releases. After this relay is released, which takes place somewhat slowly to assure that the preceding relays have released, relay Vrr also releases and closes the circuit for relay Chr and for the operation of the power magnet.

The register circuit is now again in condition to control the setting of the first group selector, because switch OM is still in the home position.

55 The register will again start the setting of the first group selector. This selector is on a contact set belonging to one of the by-pass-selectors which, of course, is not in the home position because it had just hunted in the eleventh level. The first group selector will, therefore, leave this contact set. The first free by-pass-selector will be given preference because the contact sets of the different by-pass-selectors are consecutively connected in the contact arc. The normal course will therefore be that when all desired outlets are found busy, all free by-pass-selectors will be occupied consecutively, and when the last one has tried without success to find an outlet in the desired direction, the first group selector will start again at the beginning of its arc and can start. In other words, the first hunt is for a free outlet in the first group selector arc itself.

Obviously, different variations are possible. For instance, the selectors may be tested in the out-

lets of more than one alternative level. The number of signal receivers in the register must for the purpose be increased, so that one signal receiver be provided for each alternative level.

Furthermore, other combinations of levels are possible. In Figs. 3 and 4 the outlets of the primary selectors may be so connected that no "grading" is applied, but that the outlets connected to the secondary selectors OS are common for the different multiple splits, thus simplifying the multiple connections. This may be applied also to the selectors connected to the eleventh levels in Figs. 1 and 2.

The different arrangements may be used in each or in any group selector stage.

It is also possible to perform the setting of the selectors OS in the Figs. 3 and 4 and of the selectors SGS in Fig. 5, via alternative groups of outlets. In the arrangement according to Fig. 5, if a secondary selector SGS does not find a free outlet, then the restarting of the hunting action of the primary selector PGS may take place in different ways; e. g. preference may first be given to direct outlets in the desired direction before trying to seize another secondary group selector, etc.

It should be understood that the word "level" as used in the description or definition of the terminals of switches has the same scope as "group" since, as previously stated, the invention is not limited to two-motion switches but is particularly applicable to single-motion switches in which all the contacts are in the same row.

What is claimed is:

1. In a telephone system, a plurality of lines, each designated by a multi-digit number, means including a plurality of switching stages each representing a different digit for extending a connection from a calling to a called line, a plurality of groups of switches at each stage, groups of outlets extending from the switches of one stage towards the switches of the next stage, means for rendering busy an outlet upon its selection, means including a register controller for numerically operating the switches of a stage in accordance with one digit of the called number to select a group of outlets, means operable thereupon for non-numerically actuating the last mentioned switch to select an idle one of the selected group of outlets, means operable by said register controller for operating the last mentioned switch to select an alternative group of outlets if all the outlets in the first selected groups are busy, and automatic means for variably operating the register to control the switch connected to the selected outlet, the operation being varied depending on the selection of an outlet in the first selected group or the alternative group of outlets by the preceding switch.

2. The telephone system according to claim 1, and means controlled by the register controller to reoperate the switch to hunt for an idle outlet in the first selected group if all the outlets in the alternative group are busy.

3. The telephone system according to claim 1, and means controlled by the register controller for non-numerically operating the switch connected to an alternative outlet immediately upon the selection of the latter.

4. The telephone system according to claim 1, and means controlled by the register controller for numerically operating the switch connected to an alternative outlet immediately upon the selection of the latter.

5. The telephone system according to claim 1,

and means controlled by the register controller for numerically operating the switch connected to an alternative outlet immediately upon the selection of the latter in accordance with said one digit used for first operating said switch.

6. In a telephone system, a plurality of lines, each designated by a multi-digit number, means including a plurality of successive switching stages for extending a connection from a calling to a called line, a plurality of groups of switches at each stage, groups of outlets extending from the switches of one stage directly to the switches of the next stage, means for rendering busy an outlet upon its selection, means including a register controller for operating the switches of a stage in accordance with one digit of the called number first to select a group of outlets, means operable thereupon for actuating the switch to select an idle one of the first selected group of outlets, means operable by said register controller if all the outlets in the selected group are busy for operating the switch to select one of two alternative groups of outlets, and automatic means for variably operating the register to control the switch connected to the selected outlet, the operation being varied depending whether the selected outlet belongs to the first selected or an alternative group.

7. In a telephone system, a plurality of numerically designated lines, means including a plurality of switching stages for extending a connection from a calling to a called line, groups of switches at each stage, groups of numerically designated regular outlets, each group extending from a switch of one stage to a group of switches of the next stage, means for rendering busy an outlet upon its selection, means including a register controller for operating said switches to select a group of outlets designated by a digit of the called number, means operable thereupon for actuating the switch to select an idle one of the selected group of outlets, means operable by said register controller if all the outlets in the selected group are busy for operating the switch to select as an alternative an odd numbered group of outlets if the first selected group was even numbered and an even numbered group of outlets if the first selected group was odd numbered, and means for variably operating the register to control the switch connected to the selected outlet, said operation being varied depending on the selection of an outlet in the first selected or alternative group.

8. In a telephone system, a plurality of lines, each designated by a multi-digit number, means including a first, a second and a third group of selector switches for extending a calling line towards a called line, two overflow switches, groups of outlets extending from a selector of the first group and also from the first overflow switch to the second group of selectors, other groups of outlets extending from said selector of the first group and also from the second overflow switch to the third group of selectors, means for making busy said outlets, means for operating said selector of the first group in accordance with one digit of the called number to select one of said groups of outlets, means operable thereupon for causing the last mentioned selector to hunt for an idle outlet in the selected group, means responsive to the busy condition of all the outlets of a group leading to the second group of selectors to connect the calling line over said selector of the first group with the first overflow switch, means responsive to the busy condition of all the outlets

of a group leading to the third group of selectors to connect the calling line over said selector of the first group with the second overflow switches, means for operating the overflow switches in accordance with said one digit of the called number to select a group of outlets, means for operating said overflow switches to select an idle outlet in the selected group, and means for operating the selector connected with an outlet selected by an overflow switch or said selector of the first group in accordance with the next digit of the called number.

9. In a telephone system, a plurality of lines, each designated by a multi-digit number, means including groups of first and second selectors for connecting a calling with a called line, a group of outlets extending from each first selector to a different group of second selectors, another group of outlets accessible to all groups of second selectors, groups of secondary first selectors, groups of local outlets extending between the first selectors and the secondary first selectors, connections from each secondary first selector to certain outlets extending from first selectors, means for rendering busy said outlets, means for operating a first selector in accordance with one digit of the called number for selecting a group of outlets leading to a group of second selectors, means operative thereupon for causing the first selector to hunt for an idle outlet in the selected group, means operative if all the outlets are busy in the selected group leading to the second selectors to operate the first selector to select a group of local outlets leading to the secondary first selectors, means operative thereupon for actuating the first selector to hunt for an idle outlet in the last mentioned group, means for operating the secondary first selectors in accordance with the same digit as the first selectors to select a group of outlets leading to a group of second selectors, means for operating the second selectors in accordance with the next digit, means for operating a secondary first selector to hunt for an idle outlet in the selected group, means operative if all the outlets in the selected group are busy for actuating the secondary first selector to select said group of local outlets, means operative thereupon for actuating the secondary first selector to hunt for an idle one of the local outlets, and means operative upon the selection of a local outlet by a secondary first selector for releasing the first selector through which the secondary first selector was selected and then reoperating it in accordance with said one digit of the called number.

10. In a telephone system, a plurality of lines, each designated by a multi-digit number, means including a plurality of successive switching stages each representing a different digit for extending a connection from a calling to a called line, groups of switches at each stage, each group designated by a different number of the same digit, groups of outlets, each group extending from a switch of one stage to a different group of switches of the next stage, means for rendering busy an outlet upon its selection, means including a register controller for operating a switch belonging to a first stage in accordance with a first digit of the called number to select a group of outlets leading to a group of switches of a second stage and designated by said first digit of the called number, means operative thereupon for actuating the switch of the first stage to select an idle one of the selected group of outlets, means operative by said register controller if all the outlets in the selected group are busy for operating the

switch of the first stage to select another group of outlets leading to another group of switches of the second stage, means for operating the register to control the switch of the second stage connected to the selected outlet of said selected group in accordance with a second digit of the called number, and means controlled by the register to control the switch of the second stage connected to the selected outlet of said another group of outlets to select an idle switch of the second stage designated by said first digit of the called number.

11. In a telephone system, a plurality of lines, each designated by a multi-digit number, means including a plurality of successive switching stages, each representing a different digit for extending a connection from a calling to a called line, groups of switches at each stage, each group designated by a different number of the same digit, groups of outlets, each group extending from a switch of one stage to a different group of switches of the next stage, means for rendering busy an outlet upon its selection means including a register controller and depending on the setting thereof for operating a switch belonging to a first stage in accordance with a first digit of the called number to select a group of outlets leading to a group of switches of a second stage and designated by said first digit of the called number, means operable thereupon for actuating the switch of the first stage to select an idle one of the selected group of outlets, means controlled by the calling line for variably setting the register controller in accordance with the called number, means operable by said register controller if all the outlets in the selected group are busy for operating the switch of the first stage to select another group of outlets leading to a group of switches of the second stage which are designated by a number next to the called number, means controlled by the register and depending on the setting thereof to control the switch of the second stage connected to the selected outlet of said selected group in accordance with a second digit of the called number, special connections leading from second stage switches designated by one number to second stage switches designated by the next number, means controlled by the register to control the switch of the second stage connected to the selected outlet of said another group of outlets to select an idle switch of the second stage connected to a special connection, and means controlled by the register and depending on the setting thereof for controlling the last-mentioned second stage switch.

12. In a telephone system, a plurality of lines, each designated by a multi-digit number, means including a plurality of successive switching stages, each representing a different digit for extending a connection from a calling to a called line, groups of switches at each stage, each group designated by a different number of the same digit, groups of outlets, each group extending from a switch of one stage to a different group of switches of the next stage, means for rendering busy an outlet upon its selection, means including a register controller and depending on the setting thereof for operating a switch belonging to a first stage in accordance with a first digit of the called number to select a group of outlets leading to a group of switches of a second stage and designated by said first digit of the called number, means operable thereupon for actuating the switch of the first stage to select an idle one of

the selected group of outlets, means controlled by the calling line for variably setting the register controller in accordance with the called number, means operable by said register controller if all the outlets in the selected group are busy for operating the switch of the first stage to select another group of outlets leading to a group of switches of the second stage which are designated by a number next to the called number, means controlled by the register and depending on the setting thereof to control the switch of the second stage connected to the selected outlet of said selected group in accordance with a second digit of the called number, special connections leading from second stage switches designated by one number to second stage switches designated by the next number, some of the special connections extending from each group of switches of a stage to the next highest and next lowest numbered group of switches of the same stage.

13. In a telephone system, a plurality of lines, each designated by a multi-digit number, means including a plurality of successive switching stages for extending a connection from a calling to a called line, primary and secondary groups of switches at a stage, groups of switches at the next stage, each primary and secondary group designated by a different number of the same digit, and each of the last mentioned group designated by a different number of the next digit, groups of outlets, each group extending from a primary and secondary switch of one stage to a different group of switches of the next stage, groups of special outlets from each primary group to the secondary group of switches, means for rendering busy an outlet upon its selection, a register controller variably set in accordance with the called number, means including said register controller for operating a primary switch in accordance with the register setting to select a group of outlets leading to a group of switches of the next stage, means operable thereupon for actuating the primary switch to select an idle one of the selected group of outlets, means operable by said register controller if all the outlets in the selected group are busy for operating the primary switch to select a special group of outlets leading to a group of secondary switches designated by different numbers of the same digit, means for operating the register to control the switch of the next stage connected to the outlet selected by a primary or secondary switch in accordance with its setting, and means controlled by the register to control the secondary switch connected to the selected special outlet to select an idle switch of the next stage.

14. In a telephone system, a plurality of lines, each designated by a multi-digit number, means including a plurality of switching stages for extending a connection from a calling to a called line, groups of switches at each stage, each group having a different numerical designation, a group of outlets, each group extending from a switch of one stage to a different group of switches of the next stage, means for rendering busy an outlet upon its selection, a register controller variably set from the calling line in accordance with the called number, means including said register controller for operating said switches in accordance with its setting to select a group of outlets leading to a group of switches designated by a digit of the called number, means operable thereupon for actuating the switch to select an idle one of the selected group of outlets, means operable by said register con-

troller if all the outlets in the selected group are busy for operating the switch to select a group of outlets leading to another group of switches, and automatic means for variably operating the register to control the switch connected to the selected outlet, the operation being varied depending on the group to which the selected outlet belongs.

15. In a telephone system, a plurality of lines, each designated by a multi-digit number, means including a plurality of switching stages for extending a connection from a calling to a called line, groups of switches at each stage, groups of outlets extending from each switch of one stage to a different group of switches of the next stage, means for rendering busy an outlet upon its selection, a register controller variably set from the calling line in accordance with the number of the called line, means including said register controller for operating the switches of a stage in accordance with one digit of the called number to select a group of outlets, means operable upon the numerical operation of a switch for actuating it to select an idle one of the selected group of outlets, means operable by said register controller if all the outlets in the selected group are busy for operating the switch to select another group of outlets, means for sending from the selector to the register controller a characteristic signal potential identifying the group to which the selected outlet belongs, and a device in the register responsive to said characteristic signal potential variably to control the switch connected to the selected outlet depending on the signal.
16. In a telephone system, a plurality of lines, each designated by a multi-digit number, means including a plurality of successive switching stages for extending a connection from a calling to a called line, groups of switches at each stage, groups of outlets extending from each switch of one stage to a different group of switches of the next stage, means for rendering busy an outlet upon its selection, a register controller set by the calling line in accordance with the number of the called line, means including said register controller for operating the switches of the successive stages in accordance with successive digits of the called number to select a group of outlets in a stage leading to a group of switches of the successive stage, means operable upon the termination of the numerical operation of a switch for actuating it to select an idle one of the selected group of outlets, means operable by said register controller if all the outlets in the selected group are busy for operating the switch to select another group of outlets, means for sending from the selector to the register controller a characteristic signal potential identifying the group to which the selected outlet belongs, and means in the register responsive to the characteristic signal of said another group of outlets to operate the switch connected to the selected outlet in accordance with the same digit as the switch that selected the outlet.
17. In a telephone system, a plurality of lines, each designated by a multi-digit number, means including a plurality of successive switching stages for extending a connection from a calling to a called line, groups of switches at each stage, groups of outlets extending from each switch of one stage to a different group of switches of the next stage, means for rendering busy an outlet upon its selection, a register controller set by the calling line in accordance with the number of the

called line, means including said register controller for operating the switches of the successive stages in accordance with successive digits of the called number to select a group of outlets in a stage leading to a group of switches of the successive stage, means operable upon the termination of the numerical operation of a switch for actuating it to select an idle one of the selected group of outlets, means operable by said register controller if all the outlets in the selected group are busy for operating the switch to select another group of outlets, means for sending from the selector to the register controller a characteristic signal potential identifying the group to which the selected outlet belongs, means in the register responsive to the characteristic signal of said another group of outlets to operate the switch connected to the selected outlet in accordance with a digit different from the corresponding digit of the called number.

18. In a telephone system, a plurality of lines, each designated by a multi-digit number, means including a plurality of successive switching stages for extending a connection from a calling to a called line, groups of switches at each stage, groups of outlets extending from each switch of one stage to a different group of switches of the next stage, means for rendering busy an outlet upon its selection, a register controller set by the calling line in accordance with the number of the called line, means including said register controller for operating the switches of the successive stages in accordance with successive digits of the called number to select a group of outlets in a stage leading to a group of switches to the successive stage, means operable upon the termination of the numerical operation of a switch for actuating it to select an idle one of the selected group of outlets, means operable by said register controller if all the outlets in the selected group are busy for operating the switch to select another group of outlets, means for sending from the selector to the register controller a characteristic signal current identifying the group to which the selected outlet belongs, a device in the register responsive to the characteristic signal current, means in the register for applying variable characteristic reference currents to said device in accordance with the setting of the register, and means for operating said device when the reference and signal currents bear a predetermined relationship to one-another and also when they bear another relationship to one-another for terminating the numerical operation of a switch.

19. In a telephone system, a plurality of lines, each designated by a multi-digit number, means including a plurality of successive switching stages for extending a connection from a calling to a called line, groups of switches at each stage, groups of outlets extending from each switch of one stage to a different group of switches of the next stage, means for rendering busy an outlet upon its selection, a register controller set by the calling line in accordance with the number of the called line, means including said register controller for operating the switches of the successive stages in accordance with successive digits of the called number to select a group of outlets in a stage leading to a group of switches to the successive stage, means operable upon the termination of the numerical operation of a switch for actuating it to hunt for an idle one of the selected group of outlets, means operable by said register controller if all the outlets in the selected group are busy for operating the switch to

select another group of outlets, means for sending from the selector to the register controller a characteristic signal current identifying the group to which the selected outlet belongs, a device in the register responsive to the characteristic signal current, means in the register for applying variable characteristic reference current to said device in accordance with the setting of the register, and means for operating said device when the reference current and the signal current characteristic for a group bear a predetermined relationship to one-another for terminating the numerical operation of the switch and initiating hunting in the selected group, means for operating said device when the reference current and the signal current characteristic for said another group bear a predetermined relationship to one-another for again terminating the numerical operation of the switch and initiating hunting in said another group, and means for varying the control of a selector stage by the register controller depending on the selection in the preceding stage of an outlet in one or another group.

20. A telephone system according to claim 19 and in which said device comprises two signal receivers in the register controller, means for applying a characteristic signaling current to one of said signal receivers depending on the idle or busy condition of the outlets hunted over in the selected group, means for applying to the other signal receiver a characteristic signaling current depending on the idle or busy condition of the outlets hunted over in said another group, means for operating said signal receivers when the signaling current of an idle outlet is applied thereto to terminate the hunting operation of the selector, means controlled by the last-mentioned signal receiver to cause the register controller to perform an additional operation, and means responsive thereto to cause the selector switch connected to the selected outlet of said another group to select a selector switch designated by a digit of the called number.

21. In a telephone system, a plurality of lines, each designated by a multi-digit number, means including a plurality of successive switching stages for extending a connection from a calling to a called line, groups of switches at each stage, groups of outlets extending from each switch of one stage to a different group of switches of the next stage, a register controller set by the calling line in accordance with the number of the called line, means for rendering busy an outlet upon its selection, means including said register controller for operating the switches of the successive stages in accordance with successive digits of the called number to select a group of outlets in a stage leading to a group of switches to the successive stage, means operable upon the termination of the numerical operation of a switch for actuating it to hunt for an idle one of the selected group of outlets, means operable by said register controller if all the outlets in the selected group are busy for operating the switch to select another group of outlets, means for sending from the selector to the register controller a characteristic signal current identifying the group to which the selected outlet belongs, a device comprising two signal receivers in the register controller which are responsive to signal and reference currents bearing a certain relationship to one-another, means for applying to the second signal receiver, during the initial hunting action of a selector, signaling currents characterizing the idle or busy condition of the outlets hunted over by a selector, means for

actuating said second receiver when a selector switch has hunted over and found busy all outlets in the selected group, means operable thereupon for applying to said second receiver a reference current which bears said predetermined relationship to the signaling current of said another group, and means controlled by said receivers for stopping a switch on an outlet.
